DESIGN FOR A DRESS

Philip Schlessel, New York, N. Y.

Application December 4, 1937, Serial No. 73,349

Term of patent 3½ years

To all whom it may concern:

Be it known that I, Philip Schlessel, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The characteristic feature of my design resides in the combination on the dress disclosed of the particular arrangement of horizontal, serrated pleats on the waist and sleeves, as shown.

I claim:

The ornamental design for a dress, substantially as shown, and described.

PHILIP SCHLESSEL.
